INDIVIDUAL DRINK REFRIGERATOR

Ward Leathers, Brooklyn, N. Y.

Application August 13, 1947, Serial No. 768,378

6 Claims. (Cl. 62—91.5)

1

My invention pertains to a nicer way of serving social drinks, particularly beverages iced cold but served without ice such as cocktails or champagne.

This invention comprises a refrigerating device for use atop the glass containing the drink and set thereon at the time of serving. It functions only with solidified CO₂, commonly known as "Dry Ice" which, as it evaporates, leaves no residue except CO₂ gas which is permitted in this invention to escape in a novel manner and to serve desirable functions while so doing.

The object of my invention is to keep an iced drink, whether normally served with ice as a highball, or without ice as a cocktail, colder longer after serving. Millions of persons at the cafe "cocktail hour," or in after-dinner groups, or at night clubs, are obliged to consume cocktails promptly or they lose their frigid zest, or in the case of the scotch and soda lest it be "drowned." This individual drink refrigerator, supplied with an ounce or two of "Dry Ice," will keep such drinks in pristine condition for an hour or more, i. e. longer than necessary for it to serve its useful and highly desirable purpose. It does more than that, due to the extremely low temperature of "Dry Ice" the drink becomes colder and colder, the glass almost freezes the lips and an inviting rim of hoar-frost surrounds the rim of the glass and the metal rim of the cooler.

In the case of highballs, the ice does not melt during the operational time of the refrigerator.

In order to make my invention clearly understandable to all, I have prepared the following specification and appended drawings, of which—

Fig. 1 shows in elevation a cocktail glass surrounded by a drink refrigerator.

Fig. 2 is an ornamental cap for the drink refrigerator.

Fig. 3 is a partial cross-section of the refrigerator showing one method of construction, namely, bayonet junction.

Fig. 4 is a detail of same.

Fig. 5 is a CO₂ gas flow diagram.

Fig. 6 is a partial cross-section of a highball glass surmounted by a drink refrigerator and using a friction junction.

Fig. 7 is a partial cross-section of a refrigerator illustrating a modified construction.

Fig. 8 shows in elevation a "tall" drink with a refrigerator.

Figs. 1, 2, 3, 6 and 7 are shown substantially actual size on the standard patent sheet. Figs. 4 and 5 are twice size.

A three-ounce cocktail glass 1, Fig. 1, supports

2

an individual drink refrigerator 2. The refrigerator has a dome 3 moulded of transparent plastic material, such as methyl methacrylate, topped by an ornamental finial 4 also plastic-moulded but preferably simulating amethyst, pink coral or jade, and welded to the dome. Between the dome and the glass there is a metal rim 5.

Other ornamental tops may be used as desired. By way of illustration, Fig. 2 shows the form of a polar bear, standing on a hemisphere 8, both moulded of white, opaque plastic and welded onto or into a ring 9 of the clear plastic.

The rim 5, Fig. 3, is made of stamped and plated non-ferrous metal and provided with three 15 or more rivet-pins 13 which are the male portions of the bayonet latches which hold this rim to the dome 3. The bayonet slots 15 are moulded, indented, into the sides of the dome 3, Fig. 4. An inner sheet-metal member 12, joined to the 20 rim 5 as by crimping, at 18, is formed to hold the "Dry Ice" as in a shallow dish. It also provides a seat for the soft rubber gasket 20. Small protuberances 21 at intervals along the periphery of the member 12 separate it from the glass 1 containing the drink. Through this space the 25 CO₂ gas escapes as will be seen.

Fig. 5 is a flow diagram. A block of "Dry Ice" 25 continuously evaporating turns to very cold CO₂ gas. The gas follows the course indicated by the arrows to a small opening O at the center of the member 12. Here the gas exhausts in a strong stream downward impinging on the liquid drink. The gas then flows to the rim of the glass 1 and escapes between the depressions 21. Since 30 the gas has a very low temperature, the rim 5 collects a heavy coat of hoar-frost, and the glass does the same as the cold gas travels downward along its sides. The rim 5 is designed to deflect the gas downward but it overlaps the glass only 35 very slightly for it would be highly undesirable to make the drink, especially a cocktail, look smaller than it really is.

Another structure, for serving similar purposes, is shown in Fig. 6 where the refrigerator rests atop and in operable relationship to a highball glass containing the usual highball. Liquor, when used with soda, water, ginger ale, or "coke," is chilled by pouring it over ice cubes in the service glass. Later, as the cubes melt the drink becomes watery and tasteless. It must, therefore, be consumed promptly or thrown away. My refrigerator, as shown in Fig. 6, keeps this drink so cold that the ice cannot melt, hence a further object of my invention is to conserve liquor, and legal liquor is expensive. The slightly modified

structure is composed of a moulded dome 30, a moulded supporting member 31, a moulded finial 33, and a white rubber gasket 35. The dome is preferably of transparent plastic, as is the finial 3 of Fig. 2. The finial 33 is preferably of colored plastic as is the finial 4 of Fig. 1. The member 31 may be a plated die-casting, and/or the dome 30 may be made of glass, if desired.

A modified construction, Fig. 7, is characterized by the use of a friction junction as in Fig. 6, but using stamped sheet metal parts instead of moulding or die-casting. But particularly the difference lies in the gas flow. There are connoisseurs who may claim that the mere passage of extremely cold CO₂ gas over the surface of the liquid may change the taste in some slight degree. This does not apply, of course, to drinks where any of the ingredients are already charged with CO₂ gas. In this modified construction, two stamped sheets are used. An upper sheet 34 forms the rim, the dome holder and the dish-like support for the "Dry Ice." A lower sheet 36 forms the support for the refrigerator on the rim of the glass 1. The sheets are crimped together at 37. Small perforations P in the upper sheet permit the CO₂ gas to escape to a chamber between the sheets as shown by the arrows. Escape orifices E are provided in the lower sheet outside the rim of the cocktail glass. Thus the glass contacts the lower plate at its entire periphery, incidentally avoiding spilling when serving, and the cold CO₂ gas is permitted to flow downward around the outside of the glass. In this case the rim of the upper sheet 34 and the rim of the glass 1 shortly become heavily encrusted with hoar-frost. An ornamentally milled surface 39 on the dome 40 aids in opening the refrigerator for refilling with "Dry Ice."

It should be pointed out that the refrigerating effects of the gas-flow system of Fig. 5, and that of Fig. 7, are about equal. In the case of Fig. 5, the cold gas passes in contact with the liquid and thereby constantly maintains an extremely cold atmosphere above the warmest part of the liquid. Thus the temperature differential is high, the cold gas is in constant motion and the efficiency is good. However, the contact, for heat transfer by conduction, between the glass and the metal is only partial (see Fig. 3). Here there is a loss in heat transfer efficiency not present in the method of Fig. 7. In this latter system the cold moving gas never comes in contact with the liquid, although the space between the liquid and the refrigerator is maintained at a fairly low temperature by the very cold sheets 34-36. Heat can reach the liquid only through the glass; the glass rim is in continuous contact with the sheet 32. Heat readily transfers because of the extreme temperature differential. This heat is metallically conducted to the "Dry Ice" which absorbs it readily. Thus the heat is drawn from the liquid. This method is especially recommended in the case of champagne where an unusually heavy glass stem is used.

Fig. 8 shows my individual drink refrigerator used for maintaining a non-melting condition in a "tall" iced drink such as punch, julep or lemonade.

Many other forms and constructions are obviously possible without departing from the spirit of my invention.

What is claimed is:

1. An individual drink refrigerator comprising a two-part separable container affording when assembled a chamber adapted to receive therein

a solid refrigerant capable of sublimation, said container having a bottom wall adapted to rest upon the rim of a glass drink-containing receptacle to effectively close the opening thereof, there being an opening of relatively small size formed in said bottom wall centrally thereof to permit egress of the gaseous refrigerant from said chamber into the interior of the receptacle whereby it will impinge in the form of a small stream upon the surface of liquid contained in the receptacle and flow outwardly by expansion across the surface of the liquid immediately above the same, there being a series of spaced protuberances formed on said bottom wall adjacent the periphery thereof adapted to rest upon said rim of the receptacle thereby forming between the bottom and rim a series of narrow openings to permit egress of the gaseous refrigerant from said receptacle to the atmosphere.

2. An individual drink refrigerator comprising a two-part separable container affording when assembled a chamber adapted to receive therein a solid refrigerant capable of sublimation, said container having a bottom wall adapted to rest upon the rim of a drink-receiving container to effectively close the opening thereof, there being an opening in the bottom wall to permit egress of the gaseous refrigerant from said chamber into the interior of the receptacle, there being a series of spaced protuberances formed on said bottom wall adjacent the periphery thereof adapted to rest upon said rim of the receptacle thereby forming between the bottom and rim a series of narrow openings to permit egress of the gaseous refrigerant from said receptacle to the atmosphere.

3. An individual drink refrigerator comprising a two-part separable container affording when assembled a chamber adapted to receive therein a solid refrigerant capable of sublimation, said container having a bottom wall adapted to rest upon the rim of a drink-receiving receptacle to effectively close the opening thereof, there being an opening in the bottom wall to permit egress of the gaseous refrigerant from said chamber into the interior of the receptacle, a series of spaced protuberances formed on said bottom wall adjacent the periphery thereof adapted to rest upon said rim of the receptacle thereby forming between the bottom and rim a series of narrow openings to permit egress of the gaseous refrigerant from said receptacle to the atmosphere, and means on said container for guiding the gaseous refrigerant issuing from said narrow openings downwardly along the outside of the receptacle wall.

4. An individual drink refrigerator comprising a two-part separable container affording when assembled a chamber adapted to receive therein a solid refrigerant capable of sublimation, said container having a bottom wall adapted to rest upon the rim of a drink-receiving receptacle to effectively close the opening thereof, there being an opening in the bottom wall to permit egress of the gaseous refrigerant from said chamber into the interior of the receptacle, a series of spaced protuberances formed on said bottom wall adjacent the periphery thereof adapted to rest upon said rim of the receptacle thereby forming between the bottom and rim a series of narrow openings to permit egress of the gaseous refrigerant from said receptacle to the atmosphere, and a circular flange formed on one of the container parts adapted to overlap the rim of the receptacle, the internal diameter

of said flange being slightly in excess of the external diameter of the rim of the receptacle to which the refrigerator is applied whereby gaseous refrigerant issuing from said narrow openings will be conducted downwardly along the outside of the receptacle to effectively chill the same.

5. An individual drink refrigerator comprising a domed-shaped upper shell having a peripheral lower edge and a removable bottom closure therefor, said shell and closure forming, when assembled up each other, an interior hollow chamber adapted to contain a solid refrigerant capable of sublimation, the said bottom closure having an open channel adjacent its periphery and in which channel the lower edge of the upper shell is removably seated, a gasket in said channel to effect a sealing between the lower edge of the upper shell and the bottom closure, said closure being adapted to be supported upon the rim of a drink-containing receptacle to cool the drink in the container, and the overall diameter of said closure being slightly in excess of the diameter of the rim of the receptacle.

6. An individual drink refrigerator comprising a domed-shaped non-metallic upper shell having a peripheral lower edge and a removable metallic bottom closure therefor, said shell and closure forming, when assembled upon each

other, an interior hollow chamber adapted to contain a solid refrigerant capable of sublimation, the said bottom closure having an open channel adjacent its periphery and in which channel the lower edge of the upper shell is removably seated, a gasket in said channel to effect a sealing between the lower edge of the upper shell and the bottom closure, said closure being adapted to be supported upon the rim of a drink-containing receptacle to cool the drink in the container, and the overall diameter of said closure being slightly in excess of the diameter of the rim of the receptacle.
